UNITED STATES PATENT OFFICE.

WILLIAM F. TROAST, OF LANCASTER, PENNSYLVANIA, ASSIGNOR TO THE SLAYMAKER-BARRY COMPANY, OF SAME PLACE.

DESIGN FOR A LOCK-CASE.

SPECIFICATION forming part of Design No. 26,158, dated October 6, 1896.

Application filed April 16, 1895. Serial No. 545,973. Term of patent 7 years.

To all whom it may concern:

Be it known that I, WILLIAM F. TROAST, a citizen of the United States, residing at Lancaster, in the county of Lancaster and 5 State of Pennsylvania, have invented and produced a new and original Design for Lock-Cases, of which the following is a specification, reference being had to the accompanying drawings, showing the same.

- › Figure 1 is a view of one side of a lock-case embodying my design, Fig. 2 a view of the reverse side of the same, and Fig. 3 an edge view, these three views being deemed necessary to fully illustrate my design.
- › The leading features of my design consist in the ornamentation, as shown in Figs. 1 and 2, and in the contours of the case, as illustrated in the three figures.
- › A is one side of the case; B, the reverse side; D, the edge thereof, and E centrally located bosses. (Shown in edge view in Fig. 3.)

F is the body of the case, having outwardly-curved or convex sides; G, wings on opposite sides of body F, and which taper from said body toward their outer ends, and H curved 25 or semicircular heads on the extremities of said wings.

M is the representation of a wheel located in the center of body F in relief or cameo and having its periphery falling within the 30 curved side lines of said body; N, studs in the center of heads H on side A, and R two studs on each wing G on said side A, the stud N and the studs R on each end of said side of the case forming a triangle. 35

What I claim is—

The design for a lock-case, as shown and described.

WILLIAM F. TROAST.
